UNITED STATES PATENT OFFICE.

JOHN E. SCHUSTER, OF DETROIT, MICHIGAN.

ATTACHMENT FOR SCREW-MAKING MACHINES.

Application filed October 15, 1926. Serial No. 141,774.

This invention relates to a screw delivery attachment for use in connection with machines for producing screws, and has for its object to provide, in a manner as hereinafter set forth, an attachment of such class for picking up the finished screws as they are cut off and delivering them to a container to overcome the dropping of the screws in a grease and shavings collecting pot, pan or receptacle, as is now the case with respect to the discharge of completed screws.

In automatic screw making machinery or machines in general use, the machine cuts the wire into the desired lengths and threads the same. The completed screws and steel shavings fall into a pan, and during the operation of the machine this pan gets partly filled with oil or grease. Later the operator is forced to pick the completed screws out of the mass of oil and shavings, and wash and free the screws from dirt. To overcome the foregoing objection, as well as to increase the output of the machine, is the object of an attachment in accordance with this invention, and such attachment acts to pick up the completed screws and automatically place the same in a container free of grease and steel shavings.

Further objects of the invention are to provide, in a manner as hereinafter set forth, an attachment for the purpose referred to and which is driven from the machine with which it is associated, and further whereby the attachment is strong, durable, compact, thoroughly efficient in its use, automatic in its action with respect to the delivery of the completed screws, readily installed with respect to the machine with which it is associated, and comparatively inexpensive to set up.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a front elevation of a screw

delivery attachment in accordance with this invention.

Figure 2 is a section on line 2—2 Figure 1.

Figure 3 is a section on line 3—3 Figure 1.

Figure 4 is a fragmentary view, in side elevation, of a combined grab and delivery mechanism.

Figure 5 is a fragmentary view, in rear elevation of the combined grab and delivery mechanism.

Figure 6 is a fragmentary view, in rear elevation, of the housing or cylinder.

Figure 7 is a section on line 7—7 Figure 1.

Figure 8 is a section on line 8—8 Figure 1.

Figure 9 is a section on line 9—9 Figure 1.

The screw delivery attachment for use in connection with a screw making machine is adapted to be secured to the machine with which it is associated and further driven thereby. The attachment is operated by the driving means for the tool slide of an automatic screw machine and the said driving means includes a drum B and a cam C and each of which is illustrated in dotted lines in Figure 1.

The frame of the screw machine is indicated at A, A' Figure 1 and supported thereon in a stationary manner is a tubular housing 1 which is open at each end and is mounted in upper and lower blocks 2, 3 respectively. The blocks 2, 3 are secured to the portions A, A' of the machine frame by hold fast devices 4, 4'. The housing 1 is formed intermediate its ends with a spiral slot 5 and is further formed with a lengthwise extending slot 6 which is positioned between one end of the slot 5 and one end of the housing 1. The function of the slots 5 and 6 will be presently referred to.

Secured within one end of the housing 1 is a stop member 7 or rather stop 7 formed of a sleeve of appropriate length. Secured in the other end of the housing 1 is an abutment 8 constructed from a flanged collar and with the flange 9 thereof overlapping that end of the housing 1 into which the abutment 8 is positioned. The stop 7 is of greater length than the abutment 8. The stop 7 is adjustable and is held in adjusted positions by a plurality of set screws 10.

which are mounted in the body of the housing 1 exteriorly of a pair of blocks 2, 3 at one end thereof. The abutment 8 is also adjustable and is held in its adjusted position by a pair of set screws 11 mounted in the body of the housing 1 exteriorly of the other pair of blocks 2, 3.

- The housing 1 provides a guide for a cam arm piston 12 and a grab arm piston 13.
- 10 The pistons 12 and 13 move synchronously and for such purpose a connecting rod 14 is employed. The rod 14 at one end extends through the piston 12 and the latter is adjustably secured to said rod 14. The piston 15 14 is revolvably mounted on the other end of the rod 14 and to permit of the piston 13 revolving relatively to the rod 14, the latter is provided with an annular peripheral groove 15 in which travels a pair of connecting screws 16 carried by the piston 13. The rod 14 extends into a socket 17 formed in the inner end of the piston 13 and the wall of said socket surrounds the groove 15. The piston 13 revolves on the rod 14 on the reciprocations of the piston 13 within the housing 1. The piston 12 is operated and guided in its movement by a cam arm 18 which projects laterally from the piston 12 and through the slot 6. The piston 12 is adjustably connected to the rod 14 by the set screws 19. The cam arm 18 is adjustably connected to the piston 12 by the set screw 20 and which permits of the adjusting of the arm 18 outwardly and inwardly with respect 25 to the slot 6. The cam arm 18 carries a roller 21 and which provides a rolling friction against the housing 1, as the arm 18 travels in the slot 6. The outer end of the arm 18 carries a roller 22 which provides a rolling contact between the arm 18 and the cam C. The cam C acts on the arm 18 to provide for the shifting of the piston 12 lengthwise of the housing 1 and such shift of the piston 12 will provide for the synchronous 30 shifting of the piston 13, but on the shift of the piston 13 that is to say, during the travel thereof, it will be revolved by a means to be presently referred to. Interposed between the abutment 8 and piston 13 is a coiled piston returning spring 23 which acts in conjunction with cam C in returning piston 12 and 13 from grabbing position to discharge position, travel being arrested by stop 7.
- 35 The piston 13 is formed with an opening 24 which extends diametrically thereof and adjustably positioned in said opening 24 is the shank 25 of a throw arm 26. The shank 25 is adjustably connected to the piston 13 by a set screw 27 which permits of the adjustment of said arm 26 inwardly and outwardly with respect to the slot 5. The arm 26 is provided with a roller 28 forming a rolling contact against the housing 1 when 40 arm 26 is carried with the piston 13. The

roller 28 travels in the spiral slot 5. The arm 26 is associated with the combined grab and delivery mechanism and on its travel through the slot 5 it provides for a revolving motion of the piston 13. The outer end 70 of the throw arm 26 has adjustably connected therewith, by the set screw 29 a supporting arm for the combined grab and delivery mechanism. The supporting arm is referred to generally by the reference character 30, is of yoke shape and consists of an intermediate portion 31 and a pair of end portions 32, 33. The throw arm 26 is connected to the outer end portion 33 of the supporting arm 30.

80 Associated with the throw arm 26 and carried by the housing 1, at that end of the slot 5 adjacent the abutment 8, is a dog 34 provided with a slot 35, through which extends a set screw 36 for adjustably positioning or securing the dog 34. When the throw arm 26 reaches the end of its travel, see position shown of said arm 26 in Figure 2, the roller 28 on the throw arm 26, travelling up on the dog 34 provides for a lifting motion to the grab springs which will be presently referred to and which permits of the grab springs to rise and grab screw piece on the screw machine, just as said piece is being cut off. The grab springs form 85 elements of the combined grab and delivery mechanism to be hereinafter referred to.

90 Secured to that block 3, positioned at the end of the housing 1 in which is arranged the stop 7, is a combined trip and chute supporting arm 37. The arm 37 is extended in the block 3 referred to and held tightly and adjustably by any suitable means. The arm 37 is vertically adjustable and it further supports a clevis arm 38, which carries the 95 clevis 39 and said arm 37 has connected therewith, as at 40 a hanger arm 41 for the chute 42 into which the work from the automatic screw machine is discharged. Extending through the clevis 39 is a screw pin 42' which carries a trip finger or rod 43, the latter extending through the head of the screw pin 42'. A sleeve 44 surrounds the headed end of the pin 42' and seats in the clevis 38 and through the sleeve extends the trip finger 43. A thumb nut 45 engages with the threaded terminal of the screw pin 42' and tightens the clevis 39 on the clevis pin 38, bringing or clamping sleeve 44, 110 against the clevis 39 thereby holding the trip finger 43 rigid. The function of the trip finger 43 will be presently referred to.

115 The combined grab and delivery mechanism is supported from the arm 30, see Figures 4 and 5, and includes a trip dog or latch referred to generally by the reference character 46 and which opposes the intermediate part 31 of said arm. The trip dog 46 consists of a nose portion 47 and a tail portion 48. The nose on the trip dog 46 120

is arranged at one end thereof and indicated at 49. The trip dog 46 is held in position by a controlling spring 50 therefor, that is to say that the trip dog 46 is held against the arm 30 by said controlling spring 50 and which also acts as a pivot for the dog 46. The controlling spring 50 comprises an intermediate portion 51 and a pair of oppositely disposed angle shaped end portions 52, 53. The intermediate portion 51 extends through a pair of apertured ears 54 formed on the trip dog 46 at the junction of the portions 47 and 48 thereof, and said intermediate portion 51 also extends through the portion 31 of the arm 30. The intermediate portion 51 provides a pivot for the dog 46. The intermediate portion 51 is also arranged at each side of the dog 46. The end portion 52 bears against the dog 46 and the end portion 53 bears against the portion 31 of the arm 30, see Figures 4 and 5. The spring 50 normally acts to maintain the trip dog 46 in set position.

Adjustably mounted on the portion 32 of the arm 30 is a holder 55 for a pair of oppositely disposed grab springs 56. The holder 55 is formed with a lengthwise extending opening 56 through which extends the portion 32 of the arm 30. The holder 55 furthermore is formed with a slot 58 into which extends the inner ends of the grab springs 56. A set screw 59 is carried by the holder for the purpose of adjustably connecting it to the said portion 32.

Adjustably secured to the portion 32 of the arm 30, inwardly with respect to the holder 55, is a support 60, carrying a pivot 61 for a work delivery tongue 62 consisting of a channel-shaped portion 63 and a flat work delivering portion 64 see Figures 5 and 7. The pivot 61 extends through the channel-shaped portion 63 see Figure 7 and said channel-shaped portion 63 extends in the path of the nose 49 of the trip dog 46. The delivery portion 64 of the element 62 extends between the grab springs 56. The portion 32 of the throw arm 30 extends through the support 60 and the latter is connected with said portion 32 by a set screw 67. The portion 31 of the arm 30 is provided with the diametrically disposed pin 68 positioned to one side of the intermediate portion 51 of the spring 50, and mounted on the portion 31 of the arm 30 and bearing against the pin 68 is a coiled spring 69 which also bears against the channel-shaped portion 63 of the element 62. The nose 49 of the trip dog 46 is held in engagement over the rear end of the element 62 by the spring 50. The trip finger 43 engages the tail portion 48 of the trip dog 46, which shifts the nose 49 clear of the element 62 providing for the expansion of the spring 69, whereby the latter in connection with the spring 65, 66 will operate the element 62 to discharge

the work 66 from the grab springs 56. The grab springs can be adjusted relatively to each other to take care of different kinds of work and for such purpose they are slotted for the passage of set screw 59. The set screw 59 binds the portion 59' of the holder against the springs 56 so that they will be clamped in position or to the holder 55.

The attachment is operated from the screw machine with which it is associated, drum B and cam C are elements of the screw machine and which operate the tool slide of the machine. The roller 22 provides a rolling friction on cam C. As drum B revolves, it causes cam C to push cam arm 18 back and forth. Cam arm 18 makes one complete trip over and back for each revolution of the drum B. The roller 22 rides on cam C directly ahead of the cam, not shown, which operates the tool slide of the screw machine.

When cam arm 18 is in the position shown in Figure 1, arm 26 is travelling towards the dog 34 and, as the arm 26 reaches the end of its travel, it is forced up by running up on the sloping sides of the dog 34 this in turn, pushes grab springs 56 up and they spring around the work 66, just as it is being cut off, and hold it firmly. The piece of work 66 is pushed against the portion 64 of the element 62 whereby the forward end of the element 62 is pushed down and the rear end up, about its pivot. The spring 50 then acts so that the nose 49 thereof will engage one side of the portion 63 of the element 62. The work 66 is held firmly by the grab springs 56 until the work is to be discharged therefrom. As the cam arm 18 continues to travel, cam C and spring 23 force arm 18 to travel in the slot 6 in a direction towards the stop 7, and as the pistons 12 and 13 are connected together, arm 26 is caused to travel through the spiral slot 5 in a direction towards stop 7. The travelling of the arm 26 in the spiral slot 5 will impart to the same a spiral motion, thereby carrying the combined grab and delivery mechanism and piece of work held in an arcuate path across to the opposite or front side of the machine. When the mechanism arrives at the end of its travel in such direction aforesaid, the trip finger 43 impacts the curved tail piece of the trip dog 46, shifting the dog on its pivot against the action of the spring 50, and removing the nose 49 from engagement with the portion 63 of the element 62, thereby releasing said delivery element 62, and the spring 69 which was under a state of compression, will act upon the element 62 and cause the portion 64 of said element to kick the work out of the grab springs 56 or rather deliver the work from such springs. When the work is delivered from the grab springs 56 it falls into the chute

115
120
125
130

42. The grab and delivery mechanism is now ready for return trip to its initial or normal position for the purpose of receiving another piece of work, and this operation is continuous during the operation of the tool slide and cutting off mechanism of the screw machine. The trip finger or bar 43 is adjustable, since it can be set at desired position to impact against the portion 48 of the trip dog 46. In Figure 3 arrows 70 indicate the direction of travel of the combined grab and delivery mechanism with respect to the chute 52 for the purpose of delivering the work into the latter. The grab and delivery mechanism is positioned with respect to the screw machine so that when actuated it will grab the piece of work just as it is being cut off on the last operation and then be shifted to discharge the work into the chute.

It is to be understood that although, an attachment, in accordance with this invention, as designed primarily for use with screw making machines it can be employed for machines that make bolts, studs and innumerable other objects, or in other words, a delivery attachment in accordance with this invention can be used in connection with any machine for which it is found applicable.

It is thought that the many advantages of an attachment for screw machines, in accordance with this machine, can be readily understood, and although the preferred embodiment of the invention is as illustrated and described yet it is to be understood that changes in the details of construction can be had which fall within the scope of the invention as claimed.

40. What I claim is:—

1. A screw delivery attachment for screw machines comprising a completed screw receiving means, a combined screw grabbing and delivery mechanism, and means adapted to be operated from the screw machine for shifting said mechanism bodily to and from delivery position with respect to said screw receiving means, said means including a pair of reciprocatory pistons connected together, arranged in spaced relation and traveling in unison, one of said pistons being rotatable during its travel and carrying said mechanism for shifting it to and from delivery position and the other of said pistons carrying means adapted to be operated from the screw machine to provide for reciprocation of the pistons, and supporting means for said pistons coacting with said mechanism for shifting it in an arcuate path throughout to and from delivery position.

2. A screw delivery attachment for screw machines comprising a completed screw receiving means, a combined screw grabbing and delivery mechanism, and means adapted

to be operated from the screw machine for shifting said mechanism bodily to and from delivery position with respect to said screw receiving means, said means including a pair of reciprocatory pistons connected together, 70 arranged in spaced relation and traveling in unison, one of said pistons being rotatable during its travel and carrying said mechanism for shifting it to and from delivery position and the other of said pistons carrying means adapted to be operated from the screw machine to provide for reciprocation of the pistons, and supporting means for said pistons coacting with said mechanism for shifting it in an arcuate path 80 throughout to and from delivery position, said mechanism including a latching mechanism for maintaining the delivery means latched during its bodily shifting of the mechanism, and means carried by said screw receiving means for releasing the screw delivery means for the discharge of the screw therefrom.

3. A screw delivery attachment for screw machines comprising a completed screw receiving means, a combined screw grabbing and delivery mechanism including a screw grabbing element, and a spring controlled screw delivery device independent of said grabbing element, rotatable and reciprocatory means adapted to be operated from the screw machine for bodily shifting said mechanism to and from delivery position with respect to said screw receiving means, supporting means for said rotatable and 90 reciprocatory means and coacting with said mechanism for bodily shifting it in an arcuate path throughout to and from delivery position, means for connecting said mechanism to the means operated from the screw 95 machine, and means arranged at said screw receiving means for releasing said delivery device to provide for its operation to discharge the screw from said grabbing element.

4. A screw attachment for screw machines comprising a completed screw receiving means, a bodily portable combined screw grabbing and delivery mechanism including resilient screw grabbing elements, a spring 115 controlled latch and a spring controlled screw delivery device moved into latched position with respect to said latch by and when the screw is grabbed by the grabbing elements, rotatable and reciprocatory means operated from the screw machine and carrying said mechanism for bodily shifting it to and from delivery position with respect to said screw receiving means, and means arranged at said screw receiving means to provide 120 for the actuation of the latch to release said delivery device whereby the latter will automatically operate to force the screw from said grabbing elements.

5. A screw delivery attachment for screw 125

- machines comprising a completed screw receiving means, a bodily portable combined screw grabbing and delivery mechanism including resilient screw grabbing elements, a 5 spring controlled latch and a spring controlled screw delivery device moved into latched position with respect to said latch by and when the screw is grabbed by the grabbing elements, a reciprocatory element 10 operated from the screw machine and including a rotatable member connected with said mechanism and providing means for bodily shifting said mechanism to and from delivery position with respect to said screw 15 receiving means, and means arranged at the screw receiving means to provide for the actuation of the latch to release said delivery device whereby the latter will automatically operate to force the screw from said 20 grabbing elements.

6. A screw delivery attachment for screw machines comprising a completed screw receiving means, a bodily portable combined screw grabbing and delivery mechanism including resilient screw grabbing elements, a 25 spring controlled latch and a spring controlled screw delivery device moved into latched position with respect to said latch by and when the screw is grabbed by the grabbing elements, a reciprocatory element 30 operated from the screw machine and including a rotatable member connected with said mechanism and providing means for bodily shifting said mechanism to and from delivery position with respect to said screw 35 receiving means, and means arranged at the screw receiving means to provide for the actuation of the latch to release said delivery device whereby the latter will automatically operate to force the screw from said grabbing elements, and supporting means for said reciprocatory element and coacting with said mechanism to provide for the latter to travel in an arcuate path throughout 40 to and from delivery position.

7. A screw delivery attachment for screw machines comprising a completed screw receiving means, a bodily portable combined screw grabbing and delivery mechanism including adjustable, resilient screw grabbing elements, a 45 spring controlled latch and an adjustable, spring controlled screw delivery device moved into latched position with respect to said latch by and when the screw is grabbed by the grabbing elements, a reciprocatory element operated from the screw machine and including a rotatable member carrying said mechanism and shifting it to and from delivery position with respect to 50 said screw receiving means, and means arranged at the screw receiving means to provide for the actuation of the latch to release said delivery device whereby the latter will automatically operate to force the screw from said grabbing elements.

8. A screw delivery attachment for screw machines comprising a completed screw receiving means, a bodily portable combined screw grabbing and delivery mechanism including resilient screw grabbing elements, a 55 throw arm, a spring controlled latch and a spring controlled screw delivery device moved into latched position with respect to said latch by and when the screw is grabbed by the grabbing elements, means operated from the screw machine and carrying said throw arm for bodily shifting said mechanism to and from delivery position with respect to said screw receiving means, and means arranged at the screw receiving means to provide for the actuation of the latch to release said delivery device whereby the latter will automatically operate to force the screw from said grabbing elements.

9. A screw delivery attachment for screw machines comprising a completed screw receiving means, a bodily portable combined screw grabbing and delivery mechanism including resilient screw grabbing elements, a 60 throw arm, a spring controlled latch and a spring controlled screw delivery device moved into latched position with respect to said latch by and when the screw is grabbed by the grabbing elements, means operated from the screw machine and carrying said throw arm for bodily shifting said mechanism to and from delivery position with respect to said screw receiving means, and means arranged at the screw receiving means to provide for the actuation of the latch to release said delivery device whereby the latter will automatically operate to force the screw from said grabbing elements.

10. A screw delivery attachment for screw machines comprising a completed screw receiving means, a bodily portable combined screw grabbing and delivery mechanism including resilient screw grabbing elements, a 65 throw arm and a spring controlled screw delivery device moved to latched position by and when the screw is grabbed by the grabbing elements, a pair of reciprocatory pistons connected together and traveling in unison, one of said pistons being rotatable and carrying said throw arm for bodily shifting said mechanism to and from delivery position with respect to said screw receiving means, means extending from the other of said pistons and operated from the screw machine for reciprocating the pistons, supporting means for said pistons and coacting with said throw arm to provide for the travel of said mechanism in an arcuate path throughout to and from delivery position, and means arranged at the screw receiving means to provide for the actuation of the latch to release said delivery device whereby the latter will automatically operate to force the screw from said grabbing elements.

- ceiving means to provide for the release of said delivery device whereby the latter will automatically operate to force the screw from said grabbing elements.
- 5 11. A screw delivery attachment for screw machines comprising a bodily portable combined completed screw grabbing and delivery mechanism including resilient screw grabbing elements, a throw arm, a spring controlled latch and a spring controlled screw delivery device moved into latched position with respect to said latch by and when the completed screw is grabbed by said elements, means operated from the screw machine and carrying said throw arm for bodily shifting said mechanism to and from delivery position, and means arranged at the point of delivery for the screw from said mechanism to provide for the actuation 20 of the latch to release said delivery device to force the screw from said grabbing elements.
12. A screw delivery attachment for screw machines comprising a bodily portable combined completed screw grabbing and delivery mechanism including resilient screw grabbing elements, a throw arm, a spring controlled latch and a spring controlled screw delivery device moved into latched position with respect to said latch by and when the completed screw is grabbed by said elements, means operated from the screw machine and carrying said throw arm for bodily shifting said mechanism to and from delivery position, and means arranged at the point of delivery for the screw from said mechanism to provide for the actuation of the latch to release said delivery device to force the screw from said grabbing elements,
- 25 13. A screw delivery attachment for screw machines comprising a bodily portable combined completed screw grabbing and delivery mechanism including resilient screw grabbing elements, a throw arm, a spring controlled latch and a spring controlled screw delivery device moved into latched position with respect to said latch by and when the completed screw is grabbed by said elements, means operated from the screw machine and carrying said throw arm for bodily shifting said mechanism to and from delivery position, and means arranged at the point of delivery for the screw from said mechanism to provide for the actuation of the latch to release said delivery device to force the screw from said grabbing elements,
- 30 14. A screw delivery attachment for screw machines comprising a bodily portable combined completed screw grabbing and delivery mechanism including resilient screw grabbing elements, a throw arm, a spring controlled latch and a spring controlled screw delivery device moved into latched position with respect to said latch by and when the completed screw is grabbed by said elements, means operated from the screw machine and carrying said throw arm for bodily shifting said mechanism to and from delivery position, and means arranged at the point of delivery for the screw from said mechanism to provide for the actuation of the latch to release said delivery device to force the screw from said grabbing elements,
- 35 15. A screw delivery attachment for screw machines comprising a completed screw receiving means, a bodily portable combined screw grabbing and delivery mechanism including adjustable, resilient screw grabbing elements, a throw arm, a spring controlled latch, and an adjustable, spring controlled screw delivery device moved into latched position with respect to said latch by and when the screw is grabbed from the grabbing elements, a pair of reciprocating pistons connected together and traveling in unison, one of said pistons being rotatable and carrying said throw arm and providing means for bodily shifting said mechanism to and from delivery position with respect to said screw receiving means, means extended from the other of said pistons and operated from the screw machine to provide for the reciprocation of the pistons, supporting means for said pistons and coacting with said throw arm to provide for the traveling of said mechanism in an arcuate path throughout to and from delivery position, and means arranged at the screw receiving means to provide for the actuation of said latch to release said delivery device whereby the latter will automatically operate to force the screw from said grabbing elements.
- 40 16. In testimony whereof, I affix my signature hereto.
- JOHN E. SCHUSTER.
